UNITED STATES PATENT OFFICE.

HELMUTH SELL, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A GERMAN CORPORATION.

EAR TELEPHONE.

Application filed December 14, 1922. Serial No. 606,919.

To all whom it may concern:

Be it known that I, HELMUTH SELL, a citizen of the German Empire, residing at Berlin-Charlottenburg, Germany, have invented 5 certain new and useful Improvements in Ear Telephones, of which the following is a specification.

This invention relates to improvements in telephones of that type, which are attached 10 directly to or in the human ear and which are therefore rather small. Such ear telephones are used by persons hard of hearing, or as head telephones by employees of telephone offices or other stations where permanently telephonic communications or signals 15 are received.

Telephones of such type are generally provided with a diaphragm of animal skin, preferably gold-beater's skin, onto which a 20 small iron armature is glued. Owing to the smallness of such diaphragms it is rather difficult to obtain good speech modulation, especially is it difficult to properly tension such diaphragms, because the tension is 25 largely influenced by atmospheric moisture.

The present invention relates, firstly, to improvements in the construction of telephones of this character for the purpose of obtaining improved speech modulation. 30 The magnet used is of the form of the so-called pot magnet in which the upper rim of the iron cylinder is turned in for a certain distance towards the central axis of the cylinder, terminating closely adjacent to the 35 central core of the magnet so that only a very small air gap remains to be bridged by the iron armature attached to the diaphragm. The result of this construction is that the diaphragm armature need only be 40 very small owing to the thus obtained favorable magnetic conditions. As a consequence of the lightness of the armature, the diaphragm itself can very easily follow the 45 vibrations impressed upon the armature by the arriving speech currents.

Secondly, the purpose of the present invention is to construct the telephone in such manner that it can be easily assembled for quantity production. For this purpose the diaphragm is held in place by the magnet which is movable in axial direction, and yielding means, such for instance as a spring resting against the bottom of the telephone

casing, being provided for automatically pressing the magnet against the diaphragm. 55

Lastly, the invention relates to improved means for effecting an automatic maintenance of the stress imparted to the diaphragm, for which purpose the tension ring is arranged directly on the magnet acting upon the diaphragm while said magnet is slidably located and influenced by a spring which presses the same and the tension ring against the diaphragm. 60

The accompanying drawing represents 65 suitable constructional forms of the improved arrangement, on an enlarged scale;

Fig. 1 is a central longitudinal section through a telephone adapted for persons hard of hearing; 70

Fig. 2 shows a connection diagram for said telephone, in which an induction coil serves for transmitting the speaking currents;

Fig. 3 shows part of the telephone with 75 a modification of the diaphragm tensioning means; and

Fig. 4 shows a further modification of the tensioning means.

The telephone is mounted within a casing 80 1 having a funnel-shaped front end 2 of insulating material to be introduced into the ear duct. Said front end contains a duct 3 for the sound waves, which is lined by a metal tube 4 fixed at its inner end to a disc 85 5 within said casing, which disc serves at the same time for the attachment of the diaphragm 6. The latter consists of gold-beater's skin and has a soft iron armature 7 glued to its center, its outer edge being bent over and clamped between the wall of casing 1 and a rim of disc 5. 90

Beneath the diaphragm, the magnet is arranged. The same is pot-shaped and contains a central shank 9 on which the telephone coil 10 is arranged. The shank is with its bottom piece 11 screwed into an outer cylinder 12, which has an upper inwardly projecting annular part 13 facing the projecting end of the shank 9 in such a way that the magnetic lines of force run from the central shank 9 over the diaphragm armature 7 to said annular part 13. The outer cylinder 12 of the magnet and the bottom piece 11 are, at least at one point, provided with a longitudinal slot 14 in order 100 105

not to serve as short-circuit winding. The whole magnet is preferably made of soft iron.

The exciting coil 10 is connected in series with the microphone indicated at 15 and a battery 16. Accordingly, the permanent excitation of the magnet is effected by the continuous current only. If, as shown in Fig. 2, the circuit of the magnet coil 10 is separated from that of the microphone 15 by an induction coil or by a transformer 17, it is essential that in the circuit of the telephone coil a small auxiliary battery 18 is arranged which supplies the exciting current for the telephone magnet.

The magnet 12 is slidable in axial direction within the casing 1 and carries on its upper end cylindrical ridge 19 which bears against the diaphragm 6 in such a way that the latter is pressed inwards and tensioned within the portion encircled by ridge 19 in a particularly favourable manner for the sound production. The pressure against the diaphragm 6 is produced by means of a pressure spring 20 interposed between the bottom piece 11 of the magnet and the bottom 21 of the casing 1, which bottom is preferably threaded into the casing for the purpose of easily regulating the tension of said spring.

It is of importance that the pressure spring is not tuned to the vibrations of the diaphragm 6, for which purpose it must be so chosen that its natural frequency lies beyond the frequency range of the diaphragm. Furthermore, the spring 20 can be prevented from participating in the vibrations of the diaphragm 6 by connecting large masses thereto. In this connection, the pot-shaped magnet itself can be used as such a large mass, the spring being then firmly connected with the bottom piece 11. The spring may consist of metal or of an india-rubber cushion.

The wire cable 22 for the telephone coil 10 is led to outside the casing 1 through a boring 23 in the wall of the latter. In case the bottom 21 is fixed in the casing 1, boring 23 can also be provided in this bottom.

Fig. 3 shows a modification of the tension ring, which, in this example, is formed of a thin wire split-ring 28, which, when being inserted, automatically takes-up its central position. This construction has the advantage that, with the extremely small dimensions of the parts, a wire ring can be more exactly dimensioned as to its thickness than the projection 19 made by turning. The distance of the diaphragm armature 7 from the magnet 9, 13 amounts to fractions of one millimeter only.

Fig. 4 shows a further modification of the tensioning means for the diaphragm 6: In the upper part of the casing 1 shown, a cylinder 24 is inserted, in which the dia-

phragm 6 is clamped fast by means of an inner ring 25. The latter has internal screw-threads 26, into which screws an annular stressing member 27 which bears against the diaphragm 6 and imparts to the same the necessary tension within the part encircled by it. The tension of the diaphragm 6 is in this case adjustable and controllable. The magnet (not shown) is, in this example, immovably fixed in the casing 1. While this construction has the advantage of great simplicity, the construction shown in Fig. 1 affords the possibility of automatic control of the diaphragm tension.

The invention is not limited to the constructions shown by way of example but it includes all further possibilities of construction lying within its scope.

What I claim, is:

1. An auricular telephone comprising in combination a casing, a diaphragm disposed within said casing, a magnet slidable in axial direction within said casing, and yielding means for pressing said magnet against said diaphragm near its periphery.

2. An auricular telephone comprising in combination a casing, a pot shaped magnet disposed in said casing in axial alignment therewith, said magnet having a central core and having its rim turned inwardly toward said core, a diaphragm of non-magnetic material fastened within said casing and having an iron armature attached to it throughout the whole surface of the latter, said armature bridging the air gap between the end of said shank and said turned rim.

3. An auricular telephone comprising in combination a cylindrical casing having a central sound passage at one end, a pot shaped magnet slidingly disposed in said casing, said magnet having a central core and having its rim turned inwardly toward said core, a diaphragm of non-magnetic material fastened within said casing adjacent to said sound passage and having an iron armature attached to it through the whole surface of the latter, said armature bridging the air gap between the end of said shank and said turned rim, said casing having a bottom at its other end, and a spring disposed between said bottom and said magnet, tending to force the latter against said diaphragm, said magnet having means for bearing against said diaphragm near its periphery.

4. An auricular telephone comprising in combination a cylindrical casing having a central sound passage at one end, a pot shaped magnet consisting of a cylindrical portion having its upper rim turned toward the cylinder axis, a bottom portion threaded into the other cylinder end and having a central core terminating adjacent to said inwardly turned rim and an energizing coil disposed on said core, the magnet cylinder

wall having a longitudinal slot and the bottom of said magnet having a radial slot, a diaphragm of non-magnetic material mounted in said casing adjacent to said sound passage and having an iron armature attached to its central portion, said armature bridging the air gap between said magnet core and its in-turned rim, and means for holding said magnet in said casing in operative position relatively to said armature.

5 5. An auricular telephone comprising in combination a cylindrical casing having a central sound passage at one end, a pot shaped magnet consisting of a cylindrical portion having its upper rim turned toward the cylinder axis, a bottom portion threaded into the other cylinder end and having a central core terminating adjacent to said inwardly turned rim and an energizing coil 10 disposed on said core, the magnet cylinder

wall having a longitudinal slot and the bottom of said magnet having a radial slot, a diaphragm of non-magnetic material mounted in said casing adjacent to said sound passage and having an iron armature attached to its central portion, said armature bridging the air gap between said magnet core and its in-turned rim, the upper portion of said magnet having an annular ridge adapted to bear against said diaphragm 25 near its periphery and a spring disposed between said magnet and the bottom of the casing to force said ridge against said diaphragm, the bottom of said casing being adjustable to vary the pressure of said magnet 30 against said diaphragm.

15 15. In testimony whereof I affix my signature.

20 HELMUTH SELL.
